UNITED STATES PATENT OFFICE.

CHESTER M. POETSCH AND CHARLES G. WEMLINGER, OF CHICAGO, AND CLARENCE OLSON, OF OAK PARK, ILLINOIS; SAID WEMLINGER AND SAID OLSON ASSIGNEES TO SAID POETSCH.

RADIATOR COVER AND HUMIDIFIER.

Application filed May 29, 1924. Serial No. 716,557.

This invention relates to that type of device in which a low flat cover for a radiator serves as a container for a water receptacle which is raised slightly above the top of the radiator and from which water may be evaporated to supply the air with the proper amount of humidity. Among the objects of this invention are to provide a construction of the character indicated in which the water reservoir may be moved bodily to cause a portion thereof to protrude so that the reservoir may be supplied with water; to provide in a construction of the character indicated means to cause the construction to rest firmly upon the top of the radiator so that there shall be no rocking thereof; to provide improved means whereby the structure may be attached to a radiator; to provide means for preventing the construction from becoming accidentally disconnected from the radiator; to provide, in a structure of the character described, means for easily and smoothly actuating the water container so as to avoid spilling the water contained therein; to provide means for reducing the amount of friction between the relatively sliding parts; to provide a structure of the character indicated such that the parts may be easily rearranged, if considered desirable, and without change in any structure, so that the water reservoir may be filled at either end desired; to provide a structure of the character indicated which will conceal, so far as practicable without interference with the normal functioning of the parts, the fact that there is a movable pan within the cover; to provide an improved interlocking connection between the parts to hold them in assembled relation; and such further objects, advantages and capabilities as will hereafter more fully appear.

Our invention further resides in the combination, construction, and arrangement of parts illustrated in the attached drawings, and, while we have shown therein a preferred embodiment of this invention, we desire it understood that these drawings are merely illustrative and are not to be construed as limiting our invention.

In the drawings annexed hereto and forming a part hereof, Fig. 1 is an expanded perspective view of the radiator cover and humidifier forming the subject-matter of the present invention; Fig. 2 is a fragmentary

perspective view of one end of the assembled structure; Fig. 3 is a similar view with the parts in position to permit the fluid receptacle to be filled; Fig. 4 is an expanded perspective view of one corner of the framework, showing how the parts are constructed so as to be readily and securely fastened together; Fig. 5 is a broken longitudinal sectional elevation of this construction; and, Fig. 6 is a broken transverse sectional elevation of the same.

Referring more in detail to the annexed drawings, numeral 1 designates generally a radiator, while 2, 3 and 4 denote generally a framework to be mounted on the radiator, a pan to be mounted in the frame and a cap to be mounted on the framework so as to enclose and cover the pan. A back plate 5 extends downwardly behind the radiator to prevent air currents from rising along the wall, thereby carrying dust and dirt upwardly to be deposited on any object with which the moving current of air comes in contact. The ends of the back plate 5 may be bent around at right angles, as shown at 6, or angle plates may be secured to the back plate with their edges extending forwardly for the attachment thereto of brackets 7 and 8. The upper edges of the brackets 7 and 8 lie in the same plane as the upper edge of the back plate 5. These brackets have secured to their inner faces the upturned portions 9 of the frame members 10. At their upper edges the upturned portions 9 are turned inwardly as shown at 11 and downwardly at 12 and have notches 13 provided in the downwardly extending portions 12 to cooperate with corresponding notches 14 in the webs 15 of the T-beams 16. It will be seen from the foregoing that the notches 14 in the T-beam 16 can be easily made to engage the notches 13 of the flanges 12 and when so engaged and the parts of the framework assembled as in Fig. 1, it will be impossible for them to become accidentally disengaged. However, if it is desired to knock down the framework, it is only necessary to remove the nuts and bolts 17. The back plate 5 can then be removed and the framework easily knocked down.

The plates 10 are provided with series of keyhole slots 18 for the reception of securing bolts 19 used in fastening the framework to a radiator. A yoke 20 having screw

threaded openings in or adjacent its ends cooperates with the bolts 19 in securing the framework to the radiator. In applying this structure to a radiator, the assembled framework and back plate are placed over the radiator so that the back plate extends downwardly behind the same and the cross plates 10 rest upon the top of the radiator. The yoke 20, having a pair of bolts 19 mounted in the ends thereof is then put in between two sections of the radiator and moved upwardly until the bolts go through two of the keyhole slots 18. A plate 21 is then inserted between the top of the radiator and the cross plate 10 and shoved in between the bolts 19 to cause them to move outwardly into the small ends of the keyhole slots so that the bolts cannot become accidentally disengaged from the slots. The plates 21 have two opposite edges provided with depending flanges 22 which rest upon the upper portion of the radiator and furnish solid bearing for the framework, regardless of the shape of the top of the radiator. Each of the plates 10 is provided near its outer end with a perforation 23 in which may be mounted a pivot pin 24. A lever 25 is pivotally carried by the pin 24, both of which may be mounted at either end of the construction, with the lever handle 26 extending outwardly through the slot 27 cut through the brackets 7 and flanges 9. A perforation 28 is provided in the lever 25 for the reception of a lug 29 mounted upon one end of the link 30, the purpose of which will now be described.

A shallow pan 31 has a plurality of angle pieces 32 secured to its side edges, adjacent its corners, as shown in Fig. 1. These angle pieces 32 rest upon the inner wings of the T-beam 16 and the rear member, an L-beam 16^a so that the pan may be slid endwise along the framework. Since the pan 31 is somewhat shorter than the framework this is possible. A portion of one end wall of the pan is cut away as shown at the right in Fig. 3 and has secured thereto an extension 33 which may be withdrawn through one of the slots 27 for the filling of the pan with water. Since the bottom of the extension 33 is at a higher elevation than the bottom of the pan 31, no portion of it will project below the lower edge of the end flange 34 of the top member 4. This flange 34 is cut away as shown at 35 in Fig. 1 and a piece 36 having the same size, shape and exterior finish as the piece cut out in forming the opening 35 is applied to the end of the extension 33 to constitute the end thereof. It will, therefore, be seen that when the pan 31 is completely in place, the plate 36 will appear like a portion of the flange 34 and will only be separated therefrom by a narrow line at the point of severance. This is shown clearly in Fig. 2. A plate 37 is secured by soldering or spot welding upon the under face of the pan 31 and to this plate is pivotally connected the link 30. It will, therefore, be seen that when the handle 26 of the lever 25 is actuated the lever will be turned about its pivot 24 and the opening 28 will be moved through an arcuate path to draw the link 30 outwardly. This will result in the pan 31 being moved toward the end of the framework so that the extension 33 will be projected therefrom for the purpose of pouring water thereinto. When the pan has been sufficiently filled the lever is actuated in the opposite direction to restore the pan to its normal position. The use of a lever for this purpose results in a more even movement than if the pan were pulled out by hand and, therefore, there is less tendency for the water contained in the pan to splash over and run down on the radiator and the floor. The tendency to splash is further reduced by providing a plurality of baffle plates 40 which extend from the top of the pan downwardly nearly to the bottom thereof, thus dividing the pan into several compartments and thus cutting down the size of the waves in the pan produced by movement thereof.

If it is more convenient to fill the pan at one end than at the other or if for any other reason it is desired to reverse the pan 31, this is easily done by removing the bolt 24 and lever 25 and placing them at the desired end, then placing the pan 31 with the projection 33 extending through the end of the framework where it is desired to do the filling. With the lug 29 inserted in the perforation 28 and the pan 31 in position within the framework, it is now possible to move the pan back and forth by operating the lever 26. The cap 4 is now placed upon the framework so as to include the same, together with the pan, and the assembly is complete. Water may now be placed in the pan and the lever actuated to return the extension 33 into the space within the cover and with the plate 36 in alignment with the flange 34 of the cover or cap. By reference to Fig. 6 it will be seen that there is a space 41 along the front side of the radiator cover between the lower edge of the cap flange and the upper face of the base of the T-beam 16. Through this space 41 the steam which leaves the water in the pan may pass and escape into the atmosphere, said stream mingling with the heated air which rises from the radiator and flows past the space 41.

It is, of course, understood that the specific description of structure set forth above may be departed from without departing from the spirit of our invention as set forth in this specification and the appended claims.

Having now described our invention, we claim:

1. In a radiator cover and humidifier, a frame for engaging the radiator, said frame

having a notch in one end, a pan slidably mounted in said frame and guided thereby, the end of said pan contiguous to said notch being provided with a reduced extension, a lever pivoted to said frame; means connecting said lever with said pan so as to move the pan in a manner to cause the extension to project through said notch when desired, and a cover for said frame, the combined 10 length of said pan and its extension being approximately the same as the length of said frame.

2. In a structure of the character described, a supporting frame-work to be applied to a radiator, a fluid container supported by said frame-work and having an extension projecting from one side thereof through which the container may be filled, a cover engaging said frame-work and enclosing 20 said container and having an aperture in one edge thereof positioned to register with said extension, and lever means by which the container may be moved to cause said extension to protrude through said aperture.

3. A radiator cover and humidifier comprising a hollow framework for application to the top of a radiator, said frame work having an aperture in each end, a cover having 30 means to laterally enclose the upper portion of the framework and provided at one end with an aperture positioned to register with either of the apertures of said framework, and a pan movably mounted in said framework and having an extension so positioned that upon movement of the pan said extension will be caused to protrude through the registering apertures in said framework and said cover.

4. In a radiator cover and humidifier, a hollow framework for application to the top of a radiator, said frame work having its two ends notched for the protrusion of a pan, and a pan enclosed in said framework and provided with a projection at one end adapted to be received in and to slide in either of the notches.

5. In a radiator cover and humidifier, a hollow framework for application to the top 50 of a radiator, said framework having its two ends notched for the protrusion of a pan, and a pan enclosed in said framework and provided with a projection at one end adapted to be received in and to slide in either of the notches, and a flanged cover enclosing the top of the framework and the pan, one end thereof being notched for the accommodation of the projection.

6. In a radiator cover and humidifier, a hollow framework for application to the top 60 of a radiator, said framework having its two ends notched for the protrusion of a pan, and a pan enclosed in said framework and provided with a projection at one end adapted to be received in and to slide in either

of the notches, whereby the pan is reversible within the framework, and operating mechanism shiftable from one end of the framework to the other for reciprocating the pan in either of its positions.

7. In a radiator cover and humidifier, a hollow framework for application to the top of a radiator, said framework having its two ends notched for the protrusion of a pan, and a pan enclosed in said framework and provided with a projection at one end adapted to be received in and to slide in either of the notches whereby the pan may be turned end for end in the framework for reversal thereof, a flanged cover enclosing the top 80 of the frame-work and the pan, one end thereof being notched for the accommodation of the projection of the pan, said cover being reversible to agree with the reversed pan so that the projection on the pan will slide in the notch in the cover and the other end of the cover will cover the unused notch in the end of the framework.

8. In a radiator cover and humidifier, a hollow framework for application to the top 90 of a radiator, said framework having its two ends notched for the protrusion of a pan, and a pan enclosed in said frame-work and provided with a projection at one end adapted to be received in and to slide in either of the notches, whereby the pan may be turned end for end in the framework for reversal thereof, a flanged cover enclosing the top of the framework and the pan, one end thereof being notched for the accommodation of the projection on the pan, said cover being reversible to agree with the reversed pan so that the projection on the pan will slide in one notch in the framework and the notch in the cover and the other end of the cover will close the unused notch in the end of the framework, said framework carrying a lever which protrudes through the notch in the end of the framework where it may be operated to actuate the pan so that the projection thereon will protrude from the framework or be enclosed therein.

9. In a radiator cover and humidifier, a hollow framework for application to the top 115 of a radiator, said framework having its two ends notched for the protrusion of a pan, and a pan enclosed in said framework and provided with a projection at one end adapted to be received in and to slide in either of the notches whereby the pan may be turned end for end in the framework for reversal thereof, a flanged cover enclosing the top of the framework and the pan, one end thereof being notched for the accommodation of the projection on the pan, said cover being reversible to agree with the reversed pan so that the projection on the pan will slide in one notch in the framework and the notch in the cover and the other end of the cover will close the unused notch in the end of the framework.

the framework, said framework carrying a lever which protrudes through the notch in the end of the framework, where it may be operated to actuate the pan so that the projection thereon will protrude from the framework or be enclosed therein, said lever being pivotally mounted upon the framework and being shiftable from one end thereof to the other to correspond with the 10 changed position of the pan when the latter is reversed in the framework.

10. In a radiator cover and humidifier a frame for application to a radiator, said frame having a notch at one end, a slidably 15 supported pan within said frame, said pan having an extension, and a cover shaped to fit said frame and provided with a notch positioned to register with the first mentioned notch when the cover is in place, so

that upon lateral sliding of said pan the 20 pan extension will move through said registering notches.

11. In a radiator cover and humidifier a frame for application to a radiator, said frame having a notch at one end, a slidably 25 supported pan within said frame, said pan having an extension, a cover shaped to fit said frame and provided with a notch positioned to register with the first mentioned notch when the cover is in place, and a lever connected with said pan to move said extension in and out of the said registering notches.

In witness whereof, we hereunto subscribe our names to this specification.

CHESTER M. POETSCH.
C. G. WEMLINGER.
CLARENCE OLSON.
